UNITED STATES PATENT OFFICE

MILLARD B. LUCKER, OF BENTON HARBOR, MICHIGAN, ASSIGNOR TO AUTO SPECIALTIES MFG. CO., OF SAN FRANCISCO, CALIFORNIA, A CORPORATION OF CALIFORNIA

LIFTER JACK

Application filed February 6, 1928. Serial No. 252,089.

My invention relates in general to lifting jacks and has more particular reference to a jack of the double-lift type, the main feature of which is a low initial jack height to take care of the low front axle of modern low slung automobiles especially when the tire is deflated, the jack having telescoping lifting elements adapted for extension through a lifting range sufficient to accommodate the relatively high rear axles.

Such a jack is illustrated and described in my pending application Serial No. 242,697 filed December 27, 1927 and my present invention contemplates the provision of a jack wherein the double lift principle is embodied in a somewhat simpler and more rugged mechanism than that illustrated and described in my above mentioned application.

One object of my invention is to provide in a double-lift jack, simple means for preventing the rotation of a lifting member as it is raised in the jack frame.

A further object of my invention is the provision of a friction pad engaging a lifting member whereby relative rotation of the member may be prevented as it is raised in the frame, but is not sufficiently firmly pressed upon the lifting member when the latter is rotated by a positive driving connection.

Numerous other objects and advantages of the invention will be apparent as it is better understood from the following description which taken in connection with the accompanying drawing discloses a preferred embodiment of the invention.

Referring to the drawing:

Figure 1 is a vertical cross-section taken through a jack embodying my present invention;

Figure 2 is an elevation view taken from the right in Figure 1 and showing the jack in partially and fully extended position; parts of jack being shown broken away to reveal the details of construction;

Figure 3 is a horizontal cross section taken substantially along the line 3-3 in Figure 1; and

Figure 4 is a horizontal cross section taken substantially along line 4-4 of Figure 1.

To illustrate my invention I have shown on the drawing a preferred embodiment comprising an integral retaining frame forming a base 11, a cylindrical sleeve 13 extending upwardly of the base and a bearing support 15 arranged at the top of the cylindrical sleeve. The base sleeve and bearing support are formed in one piece, and strengthening webs 17 are arranged at the junction of the parts. The bearing support 15 extends across the upper open end of the sleeve and carries a bearing 19 aligned centrally therover. The bearing support comprises a strip of material extending across the upper end of the sleeve and having downwardly extending ends which are formed integral with the sleeve, being attached to opposite sides of the sleeve, one at the top and the other at a point in the sleeve, substantially removed from the upper end of the sleeve. A bearing 31 is formed in the longitudinal end of the bearing support, that is to say, the end which is attached to the sleeve at a point substantially below its upper end. A bevel gear 21 having a hub 23 is journalled in the bearing 19 and has a toothed periphery 25 extending outwardly to engage a co-operating pinion 27 carried on a stub shaft 29 which is rotatably mounted in the bearing 31, endwise motion of the stub shaft being prevented by a shoulder 33 formed thereon. The stub shaft extends through the bearing 31 and is provided with a socket 35 having, in the illustrated embodiment, a square cross section and adapted to accommodate the squared end of an operating handle (not shown) by which the rotation of the pinion and gear may be accomplished at a distance from the jack.

The inner walls of the sleeve 13 define a cylindrical channel 37 extending through the base 11 to the upper end of the sleeve which is finished to provide a bearing seat 39. The lower end of the bearing 19 and the seat 39 are spaced apart a distance sufficient to allow the bevelled gear 21 to be slid edgewise beneath the bearing 19 and the gear may then be positioned by moving it upwardly, the hub 23 thereof sliding axially into place in the bearing. The gear 21 is supported in position by a roller bearing 41 which may be slid edge-

wise into position upon the bearing seat 39 beneath the positioned gear. The bearing 41 is provided with a central opening 43.

In the illustrated embodiment the weight 5 lifting members comprise an inner shaft 45, provided with external threads 47, extending throughout its length and an outer tube 49 having an internally threaded portion 53 at its upper end and external threads 51 are 10 formed on the tube throughout its entire length. The threads 51 are adapted to co-operate with internal threads 57 formed in the hub 23 of the gear 21, while the internally threaded portion 53 extends a short distance into the tube. The shaft 45 is assembled through the lower end of the tube 49 by engaging the threads 47 and 53. After the shaft is thus assembled, the tube and shaft may be 15 inserted in the sleeve 13 through the lower open end by sliding them longitudinally through the channel 37 and through the opening 43 in the roller-bearing 41. The opening 43 and the channel 37 being of sufficient size to accommodate the tube freely. 20 The external threads may then be mated with the internal threads 57 of the gear 21. After the tube is threaded through the gear in this manner, a peg 59 is set in the groove of the threads 51 adjacent the upper end of the tube, which peg 25 by engaging the upper end of the gear 21 limits the downward motion of the tube through the gear 21. A similar peg 59 is set in the groove of the threads 51 adjacent the lower end of the tube, which peg 30 similarly limits the upward movement of the tube through the gear 21. A pin 61 is secured in the groove of the threads 47 adjacent the lower end of the shaft 45, which pin, by engaging the lower end of the threaded 35 portion 53 limits the upward axial movement of the shaft through the tube. A load-carrying head is rigidly mounted at the upper end of the shaft 45, and the axial downward movement of the shaft through the tube 49 40 is prevented by a shoulder formed on this head.

Upon rotation of the gear 21, the lifting elements 45 and 49 being in the collapsed position illustrated in Figure 1 of the drawing, 45 the lower or tubular lifting element 49 will be raised through the gear by the co-operation of the threads 57 and 51, provided rotation of the tubular element is prevented. To prevent such rotation I have provided a friction pad or shoe 65, which is pressed, by means of a spring 71, against the outer surface of the tube. The shoe and spring are arranged in a housing 67 formed in the upper walls of the sleeve 13 and providing a 50 radial duct or channel 69 the inner end of which opens into the channel 37. The outer end of the channel or duct 69 is internally threaded to receive a retaining plug 73 for the purpose of securing the spring and the shoe in place. The housing 69 is formed in

the sleeve 13 immediately below the short end of the bearing support, that is to say, the end which is formed to the sleeve 13 in the upper end thereof, and is formed integral with the end of the bearing support so that the housing itself is hidden out of the way below the bearing support, and further is strengthened by the contiguous and integral web which forms the bearing support. The plug is provided with a slot 75 across its outer surface 75 whereby its relative position in the channel 69 may be adjusted by means of a screw driver or similar instrument in order to adjust the tension of the spring 71 and hence the force 80 of the frictional engagement between the shoe 85 and the tube.

Operation

Upon rotation of the gear 21, the tube 49 is projected from collapsed position within the sleeve by the operation of the threads 51 and 57, frictional engagement of the shoe upon the outer surface of the tube preventing the rotation of the latter. When the tube reaches the position illustrated in Figure 2 of the drawing, the peg 59 engages the lower edge of the gear and provides a positive driving connection whereby the gear rotates the tube in spite of the frictional resistance of the shoe 67. Upon rotation of the tube, a load 90 being supported upon the head 63 and preventing its rotation, the shaft 45 is projected upwardly through the tube by the operation of the threads 47 and 53 until the fully extended jack position, illustrated in dotted lines in Figure 2, is reached. Reversing the rotation of the gear 21 results in a like reversal of the lifting movements described, that is to say, the lower or tubular portion 95 100 105 110 115 120 125 130 135 140 145 150 155 160 10270 10275 10280 10285 1

friction pad 69 whereby the tubular member itself is constituted an operating member to lift the supplementary lifting member 45, the load carrying head of which by engaging 5 the load operates to prevent the rotation of the member 45 to allow the tube to perform its operating function. The peg 61 limits the relative movement of the members 45 and 49.

10 Having thus described my invention what I claim is new and desire to secure by Letters Patent is:

1. In a device of the class described, a frame providing a housing having an opening at the upper end of the frame, an externally threaded extensible member arranged in said housing for projection through the opening thereof, a driving nut journaled at the upper end of the housing and threadingly 15 engaging the extensible member, said nut having gear teeth formed in its periphery and a support member comprising a strap of width substantially less than the diameter of said nut formed integrally with and extending 20 from the side of the frame at a point below said opening, said strap extending outwardly of the frame and upwardly of said opening, a bearing formed in said strap and a driving member rotatably mounted in said bearing and having a portion extending 25 within said strap and operatively engaging the toothed periphery of said nut to form a driving connection therewith, said frame having an enlarged formation therein at the junction of said strap therewith, said formation 30 providing a duct opening into the housing, a spring pressed friction means arranged in said duct in position to enter the housing and to frictionally engage said extensible member whereby to provide a rotation preventing brake for the extensible member with respect to the frame upon the actuation of said operating member, the engagement of the extensible member and the brake means being friction solely, there being no interlocking or splined connection 35 between brake means and driving member.

40 2. In a device of the class described, a frame providing a housing having an opening at the upper end of the frame, an externally threaded extensible member arranged in said housing for projection through the opening thereof, a driving nut journaled at the upper end of the housing and threadingly 45 engaging the extensible member, said nut having gear teeth formed in its periphery and a support member comprising a strap of a width substantially less than the diameter of said nut formed integrally with and extending 50 from the side of the frame at a point below said opening, said strap extending outwardly of the frame and upwardly above said opening in spaced relationship with respect to the upper end of the frame, said strap 55 being formed with a bearing in alignment

above the opening for rotatably receiving and laterally supporting said nut, a journal formed in said strap, a driving member rotatably mounted in said bearing and having a portion extending within said strap and operatively engaging the toothed periphery of said nut to form a driving connection therewith, said frame having an enlarged formation therein at the junction of said strap therewith, said formation providing a duct 70 opening into the housing, a spring pressed friction means arranged in said duct in position to enter the housing and to frictionally engage said extensible member whereby to provide a rotation preventing brake for the extensible member with respect to the frame upon the actuation of said operating member, the engagement of the extensible member and the brake means being friction solely, there being no interlocking or splined connection 75 between brake means and driving member.

In witness whereof, I have hereunto subscribed my name.

MILLARD B. LUCKER.
